[57] CLAIM

The ornamental design for a dental instrument handle,
as shown and described.

DESCRIPTION

FIG. 1 is a perspective view of a dental instrument
handle showing my new design;

FIG. 2 is a side elevational view thereof;

FIG. 3 is an end elevational view thereof;

FIG. 4 is the opposite end elevational view thereof;
FIG. 5 is a perspective view of a second embodiment
thereof;

FIG. 6 is a side elevational view thereof;

FIG. 7 is an end elevational view thereof, the opposite
end being identical.

One side of the octagonal handle of both embodiments
has a smooth surface, the remaining seven sides have
roughened surfaces.
